UNITED STATES PATENT OFFICE.

CLARENCE E. REES, OF SAN DIEGO, CALIFORNIA.

INTERNAL-COMBUSTION ENGINE.

1,382,236.

Specification of Letters Patent. Patented June 21, 1921.

Application filed April 21, 1920. Serial No. 375,519.

To all whom it may concern:

- Be it known that I, CLARENCE E. REES, a citizen of the United States, residing at San Diego, in the county of San Diego and 5 State of California, have invented certain new and useful Improvements in Internal-Combustion Engines, of which the following is a specification, reference being had therein to the accompanying drawings.
- 10 This invention relates to internal combustion engines and more particularly to a novel valve structure therefor and it has for its object to provide a continuously rotating valve so correlated with the engine cylinder that the valve may be kept effectively cooled, may be driven from a point outside of the engine and will have its ports so located that the scavenging of the cylinder may be effectively accomplished.
- 15 It is a further object of the invention to so correlate the parts that an anti-friction bearing for the valve may be had and the valve may be continuously and automatically lubricated.
- 20 It is a further object of the invention to so correlate the parts that an anti-friction bearing for the valve may be had and the valve may be continuously and automatically lubricated.
- 25 Further objects and advantages of the invention will be set forth in the detailed description which now follows.

In the accompanying drawing—

Figure 1 is a vertical sectional view of a 30 part of an internal combustion engine having the invention applied thereto;

Fig. 2 is the detailed side view of the valve;

Fig. 3 is a detailed vertical sectional view

of the valve; and

35 Fig. 4 is a partial plan view of the valve. Like numerals designate corresponding parts in all of the figures of the drawing.

In the drawing 5 designates the engine cylinder, 6 the piston and 7 the connecting 40 rod. A water jacket 8 is spaced from the cylinder and presents an annular, upwardly facing shoulder at 9. A neck extension 10 projecting upwardly from the top of the cylinder has a threaded seat 11 at its bottom for the reception of a spark plug 12.

The neck extension projects upwardly from a web 13 which in conjunction with a spaced web 14 constitutes the cylinder head. The web 14 carries a sleeve 15 which surrounds 45 the neck extension 10 but lies in spaced relation thereto to form the annular water channel 16 therebetween. The neck extension is internally threaded at 17 for the receptacle of a closure plug 18 and the sleeve 50 15 is externally threaded at 18^a for the reception of a hose connection 19 which serves

to carry off the water from the water jacket of the engine. The cylinder head further comprises the vertical web 20 constituting a downward extension of the web 14, said web lying in spaced relation to the wall of the cylinder and the space 21 therebetween forming a continuation of a space 22 which lies between the webs 13 and 14 and is in turn a continuation of the annular channel 16. At the bottom of the web 20 the space 21 opens into an enlarged part 24 of the space 25 which lies between the wall of the cylinder 5 and the water jacket 8. About the lower edge of the web 20 there is disposed an out turned shoulder 26 which is stepped to provide a ledge 27.

A valve casing 28 comprising the inner web 29 and the outer web 30 having the water space 31 between them is provided 75 with an out turned flange 32 that is secured by cap screws 33 to the shoulder 9. The lower edge of the inner web 29 of the valve casing is adapted to have a water tight seating on the step 27 of the ledge 26. These 80 parts have been shown slightly separated in the drawing in order to preserve the clearness of the drawing but it will be understood that in practice a gasket will be employed between the contacting surfaces in 85 the usual and well known way.

A valve of inverted cup form comprising the vertical annular wall 34, a horizontal top wall 35 and vertical neck extension 36 is provided with the beveled surfaces 37 90 and 38 adapted to engage with ball bearings 39 and 40, the latter in turn being engaged by cone 41 and lock nut 42 which engage the externally threaded portion 18^a of the sleeve 15. The upper surface of the 95 top 35 of the valve contacts with the under surface of the valve casing. The under surface of the top 35 contacts with the web 14. The inner surface of the vertical wall 34 has close contact with the web 20 while the outer surface of said vertical wall has close contact with the web 29 of the valve casing. It will thus be seen that the valve is water jacketed both upon its interior and exterior; that is, a water space is disposed 100 outwardly of the valve and a water space is disposed between the valve and the engine cylinder. Furthermore the engine cylinder is water jacketed all around and over its entire head. The valve 34 is provided with 105 oblique oil grooves 44 which pick up the oil and discharge it at the top of the valve.

The top of the valve is provided with an annular oil groove 45 and ports 46 lead from the annular oil groove through the top of the valve and discharge the oil between the 5 under side of the top 35 of the valve and the upper surface of the web 14. Thus it will be seen that the oil supplied to the valve is kept in circulation so that all parts of the valve will receive adequate lubrication.

10 The valve is provided with the port 47 which, during the rotation of the valve comes into alignment with the intake and exhaust ports 48 and 49 formed in the cylinder wall adjacent the top thereof. The 15 valve casing is in turn provided with ports, only one of which is shown and indicated, 50, aligned with the port 47. The port 50 in turn communicates with a pipe 51 which may represent either an intake or an exhaust pipe. The extension 36 of the valve carries a gear wheel 52 which may be driven in any desired manner as, for example, by a gear wheel 53 and a vertical shaft 54 from any rotative part of the engine such as the 20 crank shaft, not shown.

25

I am aware of the fact that it has heretofore been proposed to provide rotary valves having ports adapted to come into registry with ports formed in the wall of 30 the engine cylinder; however it will be noted that the present invention provides simple and effective means for cooling both the valve and the entire upper part of the cylinder so that any possibility of warping 35 or binding of the valve is avoided and it will also be seen that the proportions and shape of the parts are such that undue increase in the compression space of the engine is guarded against.

40 It is to be understood that the invention is not limited to the precise construction set

forth but that it includes within its purview whatever changes fairly come within either the terms or the spirit of the appended claim.

45

Having described my invention what I claim is:

A device of the character described comprising a cylinder having a head proper and a water jacket comprising a substantially 50 horizontal wall overlying the top of the cylinder, a vertical wall extending downwardly along side the cylinder and an out turned ledge at the bottom of the vertical wall, a water jacket for the cylinder having an 55 outwardly flaring upper portion, a valve casing having spaced walls the outer of which makes water tight contact with the outwardly flaring portion of the water jacket of the cylinder and the inner of which 60 makes water tight contact with said ledge a rotative valve lying between and contacting with the valve casing and the water jacket of the cylinder head, a vertical tubular extension from the water jacket of the cylinder head, a vertical extension carried by the 65 valve, anti-friction bearings between said vertical extensions, a driving element upon the vertical extension of the valve, a vertical tubular extension from the cylinder head 70 which lies inside of the vertical tubular extension from the water-jacket of the cylinder head leaving an annular space between them, a closure for the top of the tubular extension of the cylinder head, a water conduit leading from the tubular extension of the water-jacket and a spark plug at the 75 base of the tubular extension of the cylinder head which projects into the cylinder.

In testimony whereof I hereunto affix my 80 signature.

CLARENCE E. REES.
